INFLATING-VALVE.

1,313,554.

Specification of Letters Patent.

Patented Aug. 19, 1919.

Application filed July 8, 1913, Serial No. 777,841. Renewed August 1, 1918. Serial No. 247,870.

To all whom it may concern:

Be it known that I, FREDERIK NIELSEN, a subject of the King of Denmark, and resident of Boston, in the county of Suffolk and State of Massachusetts, have invented certain new and useful Improvements in Inflating-Valves, of which the following is a specification.

This invention relates to inflating valves and embodies some of the principles embodied in the valve set forth in my copending application Serial No. 729,055 now Patent No. 1,082,232, dated December 23, 1913. In the present invention, and likewise in that set forth in said copending application, the device comprises a check valve which is operative during inflation and a main valve carried by a screw-cap, the main valve being forced against a valve seat when the screw-cap is screwed on, whereby the longitudinal movement of the main valve unseats the check valve. The two valves are caused to coact in this manner for the purpose of deflating when the screw-cap is adjusted at an intermediate position, the screw-cap being provided with vents for the escape of air when both valves are unseated. While this means of escape is very desirable and effective for deflating, it has one disadvantage which I overcome by my present improved device. This disadvantage is that when attaching the screw-cap to confine the air, the valves permit a slight loss of air, which loss cannot be entirely avoided, although if the screw-cap be screwed on promptly and as rapidly as possible the loss of air will not be appreciable. Nevertheless, if the cap be screwed on too slowly there may be an appreciable loss of air. My present improved device is adapted to reduce the loss of air to such a degree that it is negligible, even though the cap be screwed on slowly, the device nevertheless being adapted to permit as rapid deflation as desired when adjusted for deflating.

The present device embodies also an improved check valve which is adapted to be inserted into the valve body or casing from either end of the latter, the check valve and casing having co-operative portions whereby the check valve is retained and its accidental detachment prevented.

Of the accompanying drawings:

Figure 1 represents the thumb and fingers of a hand grasping the screw-cap, one of the fingers holding the main valve which is carried by the cap in position to co-operate immediately with its seat so as to prevent the loss of air while the thumb and another finger rotate the cap to screw the cap on to the valve body.

Fig. 2 represents, on a larger scale, the device included in Fig. 1, the screw-cap being shown in section and the valve in elevation.

Fig. 3 represents the valve body in section and the check valve in elevation, the check valve being held upwardly against its seat as if by air pressure within the valve body.

Fig. 4 represents, on a still larger scale, a section including a portion of the valve body and the lower end of the check valve seated therein, as shown by Fig. 3.

Fig. 5 represents a sectional view in which are combined the elements shown by Figs. 2 and 3, the screw-cap being screwed upon the valve body and the main valve which is carried by the screw-cap being firmly seated against the valve body.

Fig. 6 represents an elevation of the check valve shown by Figs. 3 and 5, in Fig. 6 the check valve being turned ninety degrees about its axis to show that the head at its upper end is narrow.

Fig. 7 represents a sectional view of the valve body.

Fig. 8 represents an elevation of a simpler form of check valve which may be inserted only through the lower end of the valve body.

Fig. 9 represents a modified form of screw-cap which is provided with a sliding sleeve adapted to cover and uncover the deflating vents.

Fig. 10 shows a modified form of screw-cap and valve, the cap being shown in section and the valve in elevation, these two parts having screw-threaded connection with each other.

The same reference characters indicate the same parts wherever they occur.

The valve body or casing is indicated at 10 in a well known form designed for pneumatic tires. It is provided with the usual

external screw-thread 11 adapted to receive a nut (not shown) for securing it in the rim of a wheel. Its upper end is reduced and provided with a screw-thread 12 for co-operation with a screw-cap indicated at 13 in Figs. 1, 2 and 5, the screw-cap having an internal screw-thread 14 for engaging the screw-thread 12. An air passageway 15 extends through the valve body 10. In this 10 passageway the valve body is provided with a seat 16 for a check valve 17, and with a seat 18 for a valve 19 which is carried by the screw-cap 13. When the screw-cap is detached and there is internal air pressure in 15 the valve body, the check valve is held against the seat by such pressure; but when the screw-cap is screwed on as far as it will go, to force the valve 19 against its seat 18, the lower end of the valve 19 engages the head 20 at the upper end of the check valve and depresses the check valve from its seat; and when the valve 19 is completely closed, as 20 shown by Fig. 5, to prevent the escape of air, the check valve drops until its head 20 rests 25 upon a shoulder 21 in the air passageway 15, as shown by Fig. 5.

The screw-cap is provided with any desired number of vents 22, for the purpose of deflating when the valves are adjusted for 30 that purpose. These vents are formed in the side of the cap, in the screw-threaded portion thereof, so that they are covered by the reduced upper end of the valve body when the cap is screwed on as far as it 35 will go. One of my present improvements enables me to place the valve 19 firmly against its seat before the threads 14 of the cap engage the threads 12 of the valve body, and to hold the valve 19 closed while screwing 40 on the cap, whereby I am able to unseat the check valve and seat the valve 19 so quickly that no appreciable quantity of air can escape. This improvement consists in providing the valve 19 with a stem 23 extending loosely through the top of the cap 13, and providing the upper end of the stem with a head 24 whereby the valve may 45 be held depressed relatively to the cap. Fig. 1 shows the cap being held by the thumb and third finger of a hand, while the index finger is engaging the head 24 to hold the valve depressed below the lower edge of the cap. The valve seat 18 is formed as 50 high as possible in the valve body, so that it constitutes the mouth of the passageway 15. Now, therefore, if the cap be grasped and the valve be depressed as shown by Fig. 1, the valve may be inserted into the mouth of 55 the valve body and firmly seated against its seat 18 without causing the cap 13 to engage the valve body. While the index finger is holding the valve seated, the thumb and third finger are free to rotate the cap 60 to screw it on to the position shown by Fig. 65

5, the cap when in this position engaging a shoulder 25 in the valve stem to keep the valve against its seat. It is now apparent that the insertion of the valve 19 is not dependent upon or retarded by the screw connection and that the manipulation of the valves and the screwing on of the cap may be effected by two wholly independent operations. The vents 22, during this operation, do not cause any loss of air. The screw-threads 12 and 14 serve to seat the valve more tightly and hold it seated. That portion of the valve which engages the seat 18 is preferably made of suitable soft material, such as rubber, in the form of a collar, the valve stem 23 having a reduced neck 26 on which the collar is arranged, and the collar is held by confronting shoulders at the ends of said neck. The rubber collar may, of course, be renewed as often as desired.

Now if the screw-cap be unscrewed only far enough to carry the vents 22 above the mouth of the valve body, the air may escape through them, because at this time the cap permits the valve 19 to open and prevents the check valve from closing, the check valve abutting against the lower end of the valve 19 and the cap holding the valves by means of the shoulder 25.

Fig. 9 shows a modified form of screw-cap whereby the loss of air may be otherwise prevented while screwing on the cap. In this form the valve 19* is provided with a stem 23* at the upper end of which is a head 24*. The cap 13* is provided with a screw-thread 14* and with vents 22* which are for the same purpose as the corresponding parts in the other form. The valve stem 23* does not extend through the crown of the cap, but the head 24* is inclosed in the crown and confined therein by a reduced throat 27, the valve being, nevertheless, capable of longitudinal movement relatively to the cap, so that the collar 19* may pass up into the cap when the cap is attached to the valve body. As the valve cannot be manipulated independently of the cap, I have provided the cap with a sliding sleeve 28 which is adapted to leave the vents uncovered when it is raised, and which is adapted to cover the vents when depressed. Near the upper end of the cap there is an annular shoulder 29 adapted to limit the upward movement of the sleeve. Between this shoulder and the reduced throat 27 the diameter of the cap is slightly less than the diameter below the throat, and the upper edge of the sleeve is turned inwardly to form a flange, as indicated at 30. This flange is adapted to engage the shoulder 29 when the sleeve is raised and to engage the shoulder at 31 when the sleeve is 35 depressed, to prevent detaching the sleeve 130

from the cap. When attaching this cap to confine the air, the sleeve should be depressed so as to cover the vents, whereby it is adapted to prevent an appreciable loss of air which would otherwise occur when the two valves are open.

The check valve shown by Figs. 3, 5 and 6 may be inserted through either end of the valve body. The upper end of the stem 32 which carries the check valve is slotted as indicated at 33 whereby the two sides are adapted to be sprung toward each other to reduce the aggregate diameter of the head 20. The head is beveled as indicated at 34 so that it is adapted to pass through the smaller portion of the air passageway 15 between the valve seat 16 and the shoulder 21. If the check valve be inserted from the lower end of the valve body, when the head 20 has passed beyond the shoulder 21 its two parts will spring back to normal position as shown and thus confine the check valve loosely in the valve body. This operation of inserting the check valve would be desirable when assembling the parts at the factory. It is possible, however, to insert the check valve through the upper end of the valve body. The valve member 17 (see Fig. 4) is in the form of a ring, and it is preferably made of soft elastic material, such as rubber. This ring is arranged between confronting shoulders 35 and 36 formed on the valve stem, and occupies an annular cavity 37 between these shoulders. If it should be desired to remove the check valve from the valve body, a suitable tool, such as a pair of sharp-pointed pincers, may be inserted into the mouth of the valve body and used to grasp the head 20 to draw the valve stem upwardly. This would require a much greater stress than the check valve would ever receive from the internal air pressure, and might result in destroying the ring 17. If the ring 17 should be destroyed, a new ring could be substituted for it, and then the check valve could be easily replaced through the upper end of the valve body, because the cavity 37 provides sufficient space into which the ring may be compressed. The insertion of the check valve would be facilitated by wetting the ring and the adjacent portion of the valve stem with saliva before inserting, and the ring would then slip easily over the shoulder 21 which is beveled, the shoulder acting to compress the ring into the cavity 37 so that the ring would pass through the smaller diameter of the air passageway. The ring would naturally expand to normal position, as shown, after passing the seat 16, and the check valve would thereupon be loosely confined in the valve body as before. The stem 32 is tapered, as indicated at 38, for the purpose of centering the check valve during its closing movement.

Fig. 6 shows the check valve turned ninety degrees about its axis with reference to the position shown by Figs. 3 and 5, in order to show that the thickness of the head 20 is reduced. This reduction is made to provide a sufficient passageway for the air, and the passageway is amplified by the slot 33. In Fig. 8 I have shown a check valve 17^x of frusto-conical formation, the same being formed integrally with the stem 32^x. With regard to the slot 33^x and the head 20^x, this device is the same as that shown by Figs. 3, 5 and 9, the only difference being the integral formation of the valve portion 17^x and the frusto-conical shape of the same. This device, of course, would be made wholly of metal, preferably brass or similar composition, and obviously could only be inserted into the valve body from the lower end.

Fig. 10 shows a cap similar to that shown by Fig. 2, except that it has screw-threaded connection with the valve stem carried thereby. In this figure the cap is indicated at 13^a, and the rubber valve member is indicated at 19^a. The cap has an internal screw-thread 14^a for engaging the thread 12 of the valve body, and it is provided with vents 22^a. The valve stem 23^a is screw-threaded, and the cap is correspondingly screw-threaded to enable the valve to be moved longitudinally in consequence of rotative movement. The head 24^a at the upper end of the valve stem is preferably knurled or otherwise formed to enable the fingers to obtain a firm grasp for rotating or screwing the valve stem relatively to the cap. This device is intended to be attached to the valve body as follows: With the parts in the position shown by Fig. 10, the valve member 19^a is inserted into the mouth of the valve body so that it engages its seat 18. When the valve member is thus seated, the lower edge of the cap is very slightly above the top of the valve body; but the space between the cap and the valve body is so slight that the thread 14^a will be brought into co-operative engagement with the thread 12 by a single rotation of the cap, such rotation causing the cap to descend relatively to the valve because of the screw-threaded connection between the valve stem and the cap. By exerting a slight downward pressure while thus screwing the cap, the valve member 19^a will be held against its seat to prevent the loss of air while effecting screw-threaded connection between the cap and the valve body. The screw-threaded connection between the valve stem 23^a and the cap provides means whereby the valve may be adjusted relatively to the valve body 10 independently of the adjustment of the cap. For example, when it is desired to deflate, the cap may be unscrewed far enough to uncover the vents 22^a. When the cap has been

adjusted to the desired position for deflating, the valve may be independently adjusted by grasping the head 24* and unscrewing the valve.

5 The ability of the valves 19, 19* and 19* to move up into their respective caps makes it possible to form the seat 18 at the upper end of the valve body instead of at a considerable distance below the upper end. It is desirable to have the valve seat as near as possible to the upper end. The collars 19, 19* and 19* may be easily replaced because their respective stems enable them to move out of the cap. The loose swivel connection between the valve stem and cap in each form permits universal movement of the rubber collar relatively to the cap and valve body, so that the valve is adapted to swing laterally to compensate for any eccentricity of 20 the valve seat or of the cap which would be likely to occur.

I claim:—

1. An inflation valve having a casing, a check valve in said casing, and a cap for 25 closing the mouth of said casing, said cap comprising a member adapted to engage said casing and having a part adapted to engage the check valve to unseat it, said member and part being relatively movable in a longitudinal direction, and said part extending through said member and being adapted to

make a tight joint with said casing whereby said part may be manipulated from the exterior to close the mouth of the casing and unseat said check valve and said member 35 may be manipulated to engage said casing and hold said part in its closed position.

2. A valve cap, forming a part independent of a tire valve construction, said cap carrying a part adapted to tightly close the 40 air-passage of a tire valve, said closing part being movable independently of said cap, having a manipulating part exterior of said cap, and having a part adapted to unseat a valve proper when said closing part is in 45 closing position, and means for retaining said closing part in closing position.

3. A cap for tire valves, comprising a portion adapted to engage a valve casing, a portion carrying a packing adapted to close the 50 end of the casing and a part for engaging a valve pin, and means for operating said last-named portion to press it toward or from the end of, the casing, said means extending to the exterior of the first-named 55 portion.

In testimony whereof I have affixed my signature, in presence of two witnesses.

FREDERIK NIELSEN.
